(No Model.)

D. A. EPPERSON.
CLOTHES RACK.

No. 254,470.

Patented Mar. 7, 1882.

D. A. EPPERSON
by C. A. Snow & Co., Attorneys
INVENTOR

UNITED STATES PATENT OFFICE.

DAVID A. EPPERSON, OF HAUBSTADT, INDIANA.

CLOTHES-RACK.

SPECIFICATION forming part of Letters Patent No. 254,470, dated March 7, 1882.

Application filed December 31, 1881. (No model.)

To all whom it may concern:

Be it known that I, DAVID A. EPPERSON, of Haubstadt, in the county of Gibson and State of Indiana, have invented certain new and useful Improvements in Clothes-Racks; and I do hereby declare that the following is a full, clear, and exact description of the invention, which will enable others skilled in the art to which it appertains to make and use the same, reference being had to the accompanying drawings, which form a part of this specification.

Figure 1 is a side view. Fig. 2 is an end view; and Fig. 3 is an end view, showing the device folded.

Corresponding parts in the several figures are denoted by like letters of reference.

This invention relates to clothes racks or driers; and it consists in certain improvements in the construction of the same, which will be hereinafter fully described, and particularly pointed out in the claim.

In the drawings hereto annexed, A A represent the sides of my improved clothes-rack, which consist of two sets of lazy-tongs made up in the usual manner of slats B pivoted together. The sides are connected by cross-pieces C, the ends of which form the pivots upon which the slats B are mounted, so as to be capable of being folded together. The ends 25 of the lower cross-pieces C project beyond the slats B on both sides of the frame, as shown at D, and to the said projecting ends D are hinged rods E, of a length about equal to the height of the frame or rack. In a similar manner the ends of the upper cross-pieces C project, as at F, and to the said projecting ends or brackets F are hinged rods G, provided upon their under sides with a series of notches, H, to receive the upper sharpened point or 35 ends of the corresponding rods E, as clearly shown in Figs. 1 and 2 of the drawings.

The operation of my invention and its advantages will be readily understood from the

foregoing description, taken in connection with the drawings hereto annexed. The frame or 45 rack is to be extended in the usual manner, and its upper and middle cross-pieces C serve to support the clothes which may be hung upon them for drying purposes. To increase the capacity of the rack the rods or arms G may 50 be extended and supported in a horizontal position by the rods E, the upper ends of which are adjusted in the notches H in the under sides of said arms. It will be seen that when the rack is but slightly extended the rods E are to be adjusted in the inner notches H, while when it is widely extended they must be adjusted in the outer notches H of the arms G, in order to insure a horizontal position of the latter.

The rods E and arms G being hinged to the projecting ends of the cross-pieces C, as herein described, they may be easily and conveniently folded against the sides of the rack, whether the latter be extended or folded. It will thus 65 be seen that they greatly increase the capacity of the rack without materially increasing the bulk.

Having thus described my invention, I claim and desire to secure by Letters Patent of the 70 United States—

As an improvement in clothes-drying racks, the lazy-tongs sides A A, connected by cross-pieces C C, having projecting ends D F, provided with hinged rods E, and hinged arms 75 G, having notches H, substantially as herein described, for the purpose shown and specified.

In testimony that I claim the foregoing as my own I have hereto affixed my signature in 80 presence of two witnesses.

DAVID A. EPPERSON.
